UNITED STATES PATENT OFFICE.

ABE N. ROSENBLoom, OF BOSTON, MASSACHUSETTS.

DESIGN FOR A TAILOR'S DRAFTING-CHART.

SPECIFICATION forming part of Design No. 32,312, dated March 6, 1900.

Application filed December 29, 1899. Serial No. 741,998. Term of patent 7 years.

To all whom it may concern:

Be it known that I, ABE N. ROSENBLoom, a citizen of the United States, residing at Boston, in the county of Suffolk and State of Massachusetts, have invented and produced a new and original Design for a Tailor's Drafting-Chart; and I do hereby declare the following to be a full, clear, and exact description of the same, reference being had to the accompanying drawing, forming a part thereof.

The accompanying drawing represents a tailor's drafting-chart embodying my design.

A in the drawing represents the body of a tailor's drafting-chart embodying my design and which has its edge extending from a point 1 to a point 2, to a point 3, and to a point 4 shaped to produce a desired pattern and one of its other edges from a point 5 to a point 6 to produce another desired-shaped pattern, said points 1 and 5 being connected by a vertical edge 7 and said chart being formed with a lower edge 8, which is on a straight line at a right angle to the edge 7. This chart is provided with the different graduated pin-holes or apertures shown. The body portion 25 of the chart is also provided with an arm 9, which extends at an angle therefrom, as shown, and said chart is also formed with a curved slot 10 and is also provided with an aperture 11, having curved edges 12 and 13. 30 14 represents another curved slot which forms a part of my design. The drafting-chart is also provided with an aperture 15 and a curved edge 13 and with a slot 16, and the said chart is also provided with a curved slot 35 17 and an interrupted curved slot 18.

Having now described my invention, what I claim as new, and desire to secure by Letters Patent, is—

The design for a tailor's drafting-chart, substantially as herein shown and described.

In testimony whereof I hereunto affix my signature in presence of two witnesses.

ABE N. ROSENBLoom.
